METAL CONTAINER

Amos Calleson and Edgar A. Calleson, Merrick,
N. Y., assignors to Crown Cork & Seal Company,
Inc., Baltimore, Md., a corporation of New York

Application March 7, 1940, Serial No. 322,809

3 Claims. (Cl. 220—27)

This invention relates to metal containers such as are employed for beverages, medicines, chemicals, foodstuffs and other similar types of commodities.

The primary object of the invention is to provide a strong, thoroughly leakproof container, which will be available to those packers who do not require or do not wish to employ a closure cap as the sealing means.

An important object of the invention is to provide a container of this character which must be severed in such a manner to permit access to the contents that the container cannot be again conveniently or economically used for commercial packaging.

Another object of the invention is to provide a container which may be opened by conventional means such as the usual can opener, and then resealed satisfactorily for domestic purposes until all of the contents have been used.

An additional object of the invention is to provide a nice appearing container which may be employed where the usual tin can might be objectionable. In this connection, the container of the present invention may be attractively decorated, and not only provides a very acceptable package, but particularly may be placed upon a dining table without being in the least obtrusive.

Before explaining in detail the present invention, it is to be understood that the invention is not limited in its application to the details of construction or the arrangements of parts illustrated in the accompanying drawings, since the invention is capable of other embodiments and of being practiced or carried out in various ways. Also, it is to be understood that the phraseology or terminology is for the purpose of description and not of limitation, and it is not intended to limit the invention claimed herein beyond the requirements of the prior art.

Referring to the drawings,

Figure 1 is a sectional view of one form of the invention,

Figure 2 is a sectional view of an additional form of the invention,

Figure 3 is a sectional view of another form of the invention.

Figure 4 is a sectional view of a further form of the invention,

Figure 5 is a sectional view of still another form of the invention,

Figure 6 is a sectional view showing a modification of the construction shown in Figure 1,

Figure 7 is a detail sectional view of the modification shown in Figure 6,

Figure 8 is a sectional view of another modification of the construction shown in Figure 6,

Figure 9 is a plan view looking into the closed upper end or neck of the container, and

Figure 10 is a sectional view of a modified form of the invention.

Containers in accordance with the present invention are preferably constructed of relatively thin sheet metal such as tin plate or steel. In 10 the form shown in Figures 1, 2, 3 and 5 to 8, the body 10 and the frusto-conical top 11 including the cylindrical neck 12 and the completely closed end 13 in which the neck terminates are integral and pressed from a single piece of metal, while 15 the inwardly concave bottom 14 is seamed to the body by an interlocked or folded seam. That is to say, the body 10, top 11, neck 12 including the integral closed end 13 thereof are seamless and devoid of side or top seams. The container 20 shown in Figure 4 has the body 10 and the bottom 14 integral as shown and formed from a single piece of metal so as to be also devoid of side and bottom seams, while the frusto-conical top 11 having the integral neck 12 and integral, completely closed end 13 is seamed to the body by a 25 folded or interlocking seam 15. In each of the constructions shown in Figures 1, 2, 3 and 5 to 8, the seamless top 11 of Figure 4 may be seamed to the seamless body 10 if desired. Also, the integral bottom 14 of the construction shown in Figure 4 30 may be employed with the containers shown in Figures 1, 2, 3 and 5 to 8; or the bottom shown in Figure 4 may be replaced by a bottom as shown in Figures 1, 5 and 6; or the bottom shown in 35 Figure 5 may be replaced by that shown in Figure 1, and the bottom shown in Figure 1 replaced by that of Figure 5. In all cases, it will be noted that the conical top 11 and associated structure is seamless, i. e., the top has an integral substantially cylindrical neck 12 closed by a likewise integral end 13 which is adapted to be punctured 40 by a suitable instrument such as the usual can opener.

Referring to Figure 1, the neck 12 at its upper 45 end is curved outwardly sufficiently as shown at 16 to form a bead, and is then curved inwardly as shown at 17 and drawn downwardly as shown at 18 to form a cup-shaped member defining a recess 19. The wall 18 may be slightly tapered 50 inwardly and downwardly, and being spaced from the wall of the neck provides a resilient seat for a stopper or cork 20. This wall 18 at its lower end has an outwardly curved portion or projection 21 resting against the inner wall of the neck as 55 shown at 22 whereby the resiliency of the wall 18

is made available to form a tight seal, and, moreover, the flat integral closed end 13 in which the bead 21 terminates is rigidly supported for receiving a puncturing tool such as a can opener. Furthermore, the wall of the recess 19 including the curved lip or bead portions 16-17 forms a smooth, continuous pouring opening. In this container, the recess 19 is produced by pressing inwardly upon the closed end of the neck 12, whereby to form the recess 19 having the side and end walls thereof integral with, i. e., in continuation of the wall of the neck 12. The bead 16-17 is of the form to receive a crown cap or other skirt form of closure, for example, as illustrated by the cap 23 in Figure 2 if it is not desired to use a resilient cork or stopper 20.

In the use of the container, the contents are filled into the container through the bottom which is then seamed as shown, and thereafter the package is complete. The consumer uses an ordinary can opener 24 to open the end 13 for dispensing the contents. In many cases, all of the contents are not used at once, and thus the stopper 20 or other closure may be employed to effect a temporary reseal. The integral end 13, however, having been severed, the container is no longer economically useful for commercially packaging, although it may be used for domestic purposes until the contents are exhausted.

The package may be furnished with a cork or stopper 20 or a closure 23 positioned as shown in Figures 1 and 2 which the consumer may remove for the purpose of puncturing the end 13 and then replace to form the reseal. As pointed out above, any suitable type of resealing closure may be employed in lieu of a stopper, e. g., caps of paper, metal or rubber preferably having a skirt and which are readily conformable to the open end of the neck to seal the same.

In Figure 2, the neck 12 is also reversely bent or drawn to produce a cup-shaped member defining a recess at its upper end and to form a cap receiving bead or finish, particularly adapted to receive a crown cap or other skirted closure, although a suitable cork or stopper may be employed. To form such a finish, the metal of the upper end of the neck is curved outwardly as shown at 25, and then inwardly as shown at 26, and then is bent outwardly and downwardly as shown at 27 to engage the inner wall of the neck 12 substantially at the point where the portion 25 begins to extend outwardly, as shown at 28. In this manner, a cup-shaped recess 29 is produced, the bottom wall of which is formed by the closed end 13 which is integral and continuous with the neck 12 and the portions 25, 26 and 27 as in the construction shown in Figure 1. By reason of this construction, the bead or finish readily receives the crown cap 23, the outwardly extending portion 25 forming a locking shoulder for the crimps present in the skirt of the cap which are indent into gripping relation with the shoulder. The bead construction shown in Figure 2 is produced by pressing inwardly upon the closed end 13 whereby the hollow cap receiving bead is formed. This container is filled in the same manner as the container described in connection with Figure 1 and has the same structural advantages. That is, once the end 13 is punctured, the container cannot be practically used for commercial packaging, although it may be satisfactorily used for domestic resealing. Also, the inner wall of the bead forms a continuous pouring outlet and the closed end 13 is rigidly supported to receive the puncturing tool. As

explained above, any suitable closure may be employed if a crown cap is not preferred.

In the construction shown in Figure 3, the neck 12 is curled outwardly to form a cap receiving finish or bead 30, and the end 13 is not depressed as shown in Figures 1 and 2, but remains in the plane of the upper end of the bead, as shown. This container is used in the same manner as the containers previously described and has substantially all of the advantages thereof. It is to be noted that the bead, in addition to providing a means for retaining a closure, also strengthens and supports the closed end 13 to receive the opener.

The container shown in Figure 4 is filled before the top 11 is applied, whereupon the top is seamed in position providing a completely sealed container as with the other forms of the invention. In opening the container, the opener 24 severs the closed end 13 which, as shown, is integral with the neck 12, and the latter is integral with the top 11. This container provides a strong article capable of resisting the high pressures developed in beverages such as beer. Moreover, once the container is opened, it is no longer useful for commercial packaging. Also, in this construction, with certain types of contents, it may be desired to resort to domestic resealing, in which event a suitable closure may be applied over the neck 12 in the manner above described.

In the construction shown in Figure 5, the container may be filled through the bottom and the latter then applied, or the bottom may be applied and the container filled through an opening 31 which may be subsequently sealed by soldering thereover a disc 32. The provision of the opening 31 and disc 32 in some cases is not preferred. As with the other containers, when the end 13 is severed, the container is no longer useful for commercial packaging, since the body, top, neck and closed end are seamless and integral, but the container may be employed for domestic resealing purposes by placing a suitable closure about the integral neck 12.

Referring to Figures 6 and 7, it is to be noted that the integral inwardly directed wall 18 of the cup-shaped member defining the recess 19 is substantially coextensive with and in contact with the wall of the neck 12 substantially throughout its length. The integral connection between the wall 18 and the neck 12 is formed into a hollow bead 33 which, upon removal of the stopper 20, will form a suitable finish for a crimped cap 23 or other skirted cap if a cork is not desired.

In Figure 8, the end of the neck 12 is severed, and a cup-shaped member 34 defining the recess 19 is positioned in the neck and has its free edge 35 and the adjacent free edge 36 of the neck interlocked by a folding seam 37. It will be noted that the wall of the cup is substantially coextensive and in contact with the wall of the neck 12, as shown in Figures 6 and 7. Also, the seam or joint 37, which extends beyond the confines of the wall of the neck, provides a bead about which may be positioned a suitable skirted closure if it is desired to reseal the container in this manner.

The constructions as shown in Figures 6, 7 and 8 are sometimes preferred for manufacturing reasons and depending upon the product which is to be packaged.

Referring to Figure 9, we have indicated the end 13 in each of the constructions shown in Figures 1 to 8 as provided with scoring 38. This

scoring is of any suitable form and assists in opening the container and forming a regular aperture. The scoring does not interfere with the seal of the container.

Referring to Figure 10, the construction is similar to that shown in Figure 1 except that the skirt 12 is provided with a circumferential indentation 40 to produce the bead or lip 41 for receiving a closure, such as one of the crimped type 23. Also, the wall 18 is straight and does not engage the neck. The cork 20 or cap 23 may be applied and used as described herein.

Each of the containers shown herein, provides a strong package, and, in addition, a nice appearing package as distinguished from conventional tin cans and bottles. Moreover, the container of this invention may be suitably decorated and used upon the dining table where in some cases, bottles or tin cans would not be entirely harmonious.

The container body 10 with integral neck and top is formed by successively drawing a cup-shaped blank to the contour illustrated in Figures 1, 2, 3, 5 and 6 to 8 so as to produce a seamless container except for the bottom which is seamed or otherwise united to the body. The container shown in Figure 4 wherein the bottom 14 is integral with the body 10 is also formed by drawing a cup-shaped blank and the independent top 11 with neck 12 is similarly drawn.

In drawing, the neck is least subjected to the drawing operation and consequently the metal thereof may be bent and formed as by drawing to provide a structure embodying the neck and bead such as shown in Figures 1, 2, 3, 6 and 7 without danger of cracking the metal or otherwise weakening the neck or bead. This is important in that it permits the application of crimped caps by automatic machinery, as well as the prying off of such caps without danger of distortion. Moreover, the neck is rigidified,

and the usual can opener may be applied to afford easy opening of the closed end 13.

This application is a continuation-in-part of our application Serial No. 223,992, filed August 9, 1938.

We claim:

1. A metal container having a body, a top and a cylindrical neck integral with the top, the metal at the upper end of the neck being curved outwardly beyond the wall of the neck and upwardly and inwardly to form a hollow circumferential, external closure receiving bead, the metal from said bead being continued downwardly to form an integral substantially cup-shaped internal closure receiving portion having a smooth pouring opening adjacent said bead, said cup-shaped portion having an integral continuous closed end positioned within the neck and adapted to be opened by a puncturing tool to permit removing of the contents, the outer surface of the side wall of the cup-shaped portion being in circumferential contact with the adjacent inner surface of the wall of the neck, whereby the closed end of the cup-shaped portion is rigidly supported for receiving the puncturing tool.

2. A metal container in accordance with claim 1 wherein the outer surface of the side wall of the cup-shaped portion is in circumferential contact at the lower end of the cup-shaped portion with the adjacent inner surface of the wall of the neck.

3. A metal container in accordance with claim 1 in which the outer surface of the side wall of the cup-shaped portion is in circumferential contact with the adjacent inner surface of the wall of the neck substantially throughout the length of the cup-shaped portion below the bead.

AMOS CALLESON.
EDGAR A. CALLESON.
